UNITED STATES PATENT OFFICE.

JOHN A. SMITH, OF PHILADELPHIA, PENNSYLVANIA.

FLOWER-STAND.

1,073,874.

Specification of Letters Patent.

Patented Sept. 23, 1913.

Application filed December 13, 1912. Serial No. 736,461.

To all whom it may concern:

Be it known that I, JOHN A. SMITH, a citizen of the United States, residing at Philadelphia, in the county of Philadelphia and State of Pennsylvania, have invented 5 certain new and useful Improvements in Flower-Stands, of which the following is a specification.

The object of my invention is to provide a 10 flower stand of novel, simple and efficient construction adapted to support floral wreathes and other floral pieces in different positions.

Accordingly, the invention, as generally 15 stated, consists in the provision of a suitable supporting standard and a frame adjustably supported thereon and provided with means to support floral pieces at an incline and constructed to be folded into small 20 compass for shipment, as will be hereinafter fully described and particularly claimed.

In the accompanying drawings, illustrating 25 my invention: Figure 1, is a perspective view of my improved flower stand. Fig. 2, is a side elevation of a part of the standard 30 and the adjustable frame thereon. Fig. 3, is a front view of the adjustable frame. Fig. 4, is a perspective view of the adjustable frame folded for shipment.

Referring to the drawings, 2 designates a 35 vertical standard provided at its lower end with suitable, foldable supporting legs 3. The standard 2 is adapted to support one or more frames 4, and each frame 4 is of the following construction: 5 designates a flat bar arranged on one side of the standard 2 and at an incline with relation thereto, as shown. The upper end of the bar 5 is bent to form a loop extending horizontally from 40 the inclined portion of the bar and comprising upper and lower horizontal arms 6 and 7, respectively, and a vertical arm 8 connecting the horizontal arms. The arms 6 and 7 are provided with alined openings through 45 which the standard 2 extends and to which the standard 2 is slidably fitted, so that the frame 4 may be adjusted vertically upon the standard. To secure the frame 4 in its positions of vertical adjustment on the standard 50 2, I provide a set screw 9 which is screwed into and through the vertical arm 8 of the loop and is engaged with the standard 2 between the arms 6 and 7. The free end of the upper arm 6 is bent and extended up-

wardly and forms a projection 10 above the 55 upper end of the inclined portion of the bar 5 and adjacent the standard 2 in spaced relation thereto, for a purpose presently explained. Mounted on the inclined portion of the bar 5 is a flat bar 11 which is pivoted 60 about midway of its ends to the central part of the inclined portion of the bar 5 by a suitable rivet 12. The bar 11 is adapted to be adjusted around the axis of the rivet 12 and to be held in positions of adjustment by frictional contact with the bar 5.

When the frame 4 is in the position shown in Fig. 1, it is secured to the standard 2 by the set screw 9 and the bar 11 is adjusted to extend at right angles or any other desired 70 angles to the bar 5. In this position of the parts, the upper portion of a floral piece, a wreath for example, shown by dotted lines in Fig. 1, is hooked over the projection 10 and the floral piece rests at an incline upon 75 the bar 5 and the bar 11, the latter bar preventing the lateral tilting or rocking of the floral piece. The portion of the standard 2 back of the projection 10 serves to prevent rearward displacement of the upper end of 80 the floral piece and the projection 10 prevents forward displacement and prevents the floral piece from sliding downwardly upon the bars 5 and 11.

When it is desired to pack or ship the 85 stand, the set screw 9 is loosened, the frame 4 is moved upwardly from the standard 2 and the bar 11 is adjusted on the rivet 12 to lie parallel to the bar 5, as shown in Fig. 4.

I claim:

1. In a flower stand, the combination of a supporting standard, a frame slidably fitted to the standard, and means for securing the frame to the standard, said frame including an inclined part arranged on one side of the 95 standard and an upwardly-extending projection arranged on the same side of the standard above the upper portion of the inclined part and adjacent the standard in spaced relation thereto, whereby a supporting pocket is formed by said standard and said projection.

2. In a flower stand, the combination of a supporting standard, a frame including an inclined bar having its upper end formed 105 into a loop comprising upper and lower arms and a connecting arm, said upper and lower arms having alined openings through

which the standard extends, and said upper arm having an upwardly extending free end adjacent the standard and in spaced relation thereto, and means for securing said 5 loop to the standard, whereby a supporting pocket is formed by said standard and said projection.

In testimony whereof I affix my signature in presence of two witnesses.

JOHN A. SMITH.

Witnesses:
